UNITED STATES PATENT OFFICE.

SEBASTIAN FERRIGNO, OF BROOKLYN, NEW YORK.

FOOT-SUPPORT.

1,241,839.

Specification of Letters Patent.

Patented Oct. 2, 1917.

Application filed February 1, 1917. Serial No. 145,857.

To all whom it may concern:

Be it known that I, SEBASTIAN FERRIGNO, a citizen of the United States, and a resident of the borough of Brooklyn, county of 5 Kings, city and State of New York, have invented certain new and useful Improvements in Foot-Supports, of which the following is a specification.

My invention relates to means for supporting the foot during the operations of boot or shoe polishing, blacking or the like, and is designed to afford simple but effective clutch mechanism whereby the foot gear may be conveniently and quickly 10 secured in position or released therefrom, as hereinafter fully set forth—the invention consisting in the specific construction and arrangement of parts described and claimed, and the distinctive feature being the use of 15 telescopic screws for effecting the manipulation of the clamp jaws, whereby all are 20 moved simultaneously.

In the accompanying drawings,

Figure 1, is a side elevation of a foot rest 25 embodying the essential features of my invention;

Fig. 2, is a section taken upon plane of line 2—2, Fig. 1, and looking upward toward the under side of the foot plate, this 30 figure also including views of the upper sides of the clamp members, detached from the foot plate.

The inclined foot plate A, forms the upper extremity of a standard A', of any 35 desired or suitable construction, and which is bolted to the floor or other appropriate support B. The foot plate A, may be formed with a heel gage or shoulder a, to aid in positioning the boot or shoe on said foot 40 plate in proper relation to the clamping mechanism.

H, H, are the heel clamps, and S, S, the sole clamps.

Each clamp-member is formed with a slot 45 representing approximately the arc of a circle, the curve being reversed in each pair. Thus the heel-clamps H, H, are formed with oppositely inclined slots h, h, while the sole-clamps S, S, are similarly formed with 50 oppositely inclined slots s, s. The heel-clamps H, H, are movably supported on the under side of the foot plate A, by means of headed screws h', h', the shanks of which pass through said slots h, h, and form fulcrum posts for the said clamp-members 55

H, H, while the heads of the screws constitute flanges upon which said clamp-members are slidably suspended. In like manner the sole-clamping members S, S, are supported upon the under side of the foot plate A, by headed 60 screws s', s', the shanks of which pass through the slots s, s, forming fulcrum posts, while the heads perform the function of rests for the under sides of said clamp-members S, S.

The outer end of each heel-clamp H, is formed with an up-turned jaw h², extending above the upper surface of the foot plate A, while its inner end is formed with a hole h³, to accommodate the head of a screw h⁴, 70 (see Fig. 1) by which the heel clamp H, is pivotally connected with the traveling nut block N, on the heel screw H'. In corresponding manner the outer ends of each sole-clamp S, is formed with a jaw s², projecting above the foot plate A, and with a hole s³, at its inner end for the accommodation 75 of the head of a screw s⁴, (see Fig. 1) by which the sole clamp is pivotally connected with the traveling nut N', on the sole 80 screw S'.

The inner end of the sole screw S', is hollow and is formed with a female screw thread for the reception of the male thread of the heel screw H',—the peripheral thread of the 85 heel screw H', and the internal thread of the sole screw S', being reversed in inclination as related to the thread on the periphery of said sole screw S', so that when the latter is turned axially by means of its handle 90 S'', or equivalent means, in either direction, and either the heel jaw h² or the sole jaw s² meets with even slight contactual resistance, the heel screw H', will be caused 95 to rotate, and hence the nuts N, N', may be made to advance toward or recede from each other by the proper manipulation of the handle S'.

It will be understood that the screw S' 100 may be caused to advance or recede on the screw H' if the resistance between said screws is less than the resistance between either of the screws and the corresponding nut.

The outer portion of the heel screw H', 105 rests loosely in a guide sleeve a', formed for its lateral support in the standard A', and a similar guide sleeve a², is formed in said standard A', for the lateral support of the shank of the sole screw S',—both screws

being free to move longitudinally through said supporting guide sleeves α' , α^2 .

The telescoping of the two screws H' , S' , is an important factor in attaining a compact and effective construction and arrangement of parts whereby I am enabled to simultaneously and quickly, and conveniently apply or retract both heel and sole clamps by the simple manipulation of a single part,—the handle S'' ,—it being understood that the motion imparted to the nuts N , N' , by their respective screws is utilized to swing the clamping members H , S , on their respective fulcrum post (*i. e.* the shanks of the screws h' , s') so as to bring the jaws h^2 , s^2 , into or out of commission, as desired.

Copies of this patent may be obtained for five cents each, by addressing the "Commissioner of Patents, Washington, D. C."

What I claim as my invention and desire to secure by Letters Patent is,

In a foot support of the character designated, the combination with the foot plate of heel and sole clamps pivotally supported on the under side thereof, traveling nuts pivotally connected with said clamps, and screws upon which said traveling nuts are mounted, said screws telescopically engaging and threaded the one with the other, and means for manipulating said screws to advance or retract the clamps. 20 25

SEBASTIAN FERRIGNO.
